UNITED STATES PATENT OFFICE.

PETER E. LITTLE, OF DAYTON, OHIO, ASSIGNOR TO THE OHIO RAKE COMPANY, OF SAME PLACE.

HARROW.

SPECIFICATION forming part of Letters Patent No. 423,523, dated March 18, 1890.

Application filed October 22, 1887. Renewed November 29, 1889. Serial No. 331,866. (No model.)

To all whom it may concern:

Be it known that I, PETER E. LITTLE, a citizen of the United States, residing at Dayton, in the county of Montgomery and State of Ohio, have invented certain new and useful Improvements in Harrows, of which the following is a specification.

My invention relates to that class of harrows having jointed beams armed with disks and controlled in such manner as to be set at different angles to the line of draft; and it relates primarily to improved means for connecting or jointing the harrow-beams to the draft beam or head, consisting in a certain construction of the hinged joint at the outer end of the draft-beam and between it and the harrow-beam, whereby the harrow-beam is permitted to rise and fall pivotally in a vertical plane, and to swing back and forth pivotally in a horizontal plane, but is restrained from rocking movement, and, secondly, to such general features of the machine and to such subordinate details of construction as may be hereinafter described and claimed.

In the drawings, Figure 1 is a side elevation of a harrow embodying my invention, with the nearer end of the gang or harrow beam removed and the draft-beam in section. Fig. 2 is a side elevation, enlarged, of one of the harrow-disks with the gang-beam above in section, showing my improved scraper in connection with said beam and acting upon the disk in its proper relative position; Fig. 3, an enlarged detail of said scraper with a portion of the harrow-disk in section and a part of the scraper-bracket broken away to show the pressing-spring and the means whereby its tension is adjusted, all seen from the rear; and Fig. 4, a like detail from the front, except that the entire disk is shown in transverse section, seen from the top. Fig. 5 is an enlarged detail of said scraper and a portion of said disk in horizontal section, seen from the top; Figs. 6, 7, and 8, enlarged details of the hinged joint between the draft-beam and gang or harrow beams, respectively in transverse section, top plan view, and front elevation; Fig. 9, a section through said joint on the line indicated by corresponding letters

in the sixth figure, and Fig. 10 an enlarged detail of that member of said joint which more appropriately is attached to the harrow-beam or gang-beam.

A is the draft-tongue, having at its rear end 55 the inclined standard A', bearing an appropriate seat and beneath said standard having the rigidly affixed transverse frame-bar or draft-beam B, which extends to nearly the entire width of the harrow equidistant upon 60 each side. To this draft-beam, beneath its outer ends, are pivoted at a point near their own outer ends the two gang or harrow-beams C, extending from the pivotal points inward until they nearly meet, being allowed to rise 65 and fall vertically and swing back and forth upon their pivotal connection with the draft-beam, but at no time to rock thereupon. Each of these gang-beams supports a gang of disks D, which revolve upon a shaft, rod, or 70 journal D, carried in bearings at the lower end of hangers E, depending from the gang-beams near each end thereof and the inner brackets; or else the inner ends of the beams are connected by links e, with the lower end 75 of a lever E', pivoted to and latching into a segment-rack E² upon the draft-tongue.

As thus far briefly described, the machine in its general features does not differ materially from others heretofore in use. 80

The hinge-joint between the draft-beam and the respective gang-beam at that side of the draft-tongue is constructed as follows: A plate F is secured to the top of the gang-beam and provided at each end with ears or offsets f' 85 f², rising slightly and curving, respectively, to the front and rear, and near their ends rounded into trunnions or journals. The rear offset is prolonged beyond the journal part into a downwardly-extending hook f³, but inside the 90 journal has an upwardly-extending shoulder f⁴, to serve as a stop against endwise movement. To the draft-beam is bolted a rear bracket H', having a downwardly-extending eye-lug h', and also having inside of this 95 bracket and above the bearing-point a shoulder h², reversely set to the shoulder upon the rear offset to engage therewith. The front bracket I', also bolted to the draft-beam, has two lugs i', placed at a distance apart corre- 100

sponding with the length of play desired in the angular adjustments of the harrow-gangs and connected above by a depending horizontal flange i^2 , the edge of which forms the 5 upper member of the guide for the front journal of the lower plate. The lugs receive a bolt I^2 beneath and parallel with this flange and at such distance therefrom as to form therewith a horizontal guideway i^3 , and of 10 such diameter as to practically prevent any vertical movement of the front journal or trunnion. The upper brackets may also be connected by a horizontal eyebolt K , which will serve also as a hound-bolt. In assembling 15 the parts of this hinged joint it will be understood that the bolt I^2 , which herein performs the office of assembling-bolt, will be removed. Then the rear trunnion of the plate upon the gang-beam will be hooked into 20 the eye depending from the rear bracket on the draft-beam, and the gang-beam will be rocked upward until the two trunnions have been brought into horizontal position and both the draft-beam and gang-beam are parallel. This will bring the shoulder on the 25 rear offset against the shoulder of the rear bracket, and will bring the front trunnion practically against the upper edge of its guideway, when the assembling-bolt will be slipped into place, secured by its key, and the fastening be complete. The gang-beam will then be free to rise and fall vertically 30 upon the bearings for the trunnions afforded by the eye and guide and to be adjusted singularly, as the beam in swinging horizontally 35 will carry the front trunnion with it along the guide formed by the front bracket and the horizontal bolt thereon, the rear trunnion hinging or swiveling in the eye of the rear 40 bracket in such movement; but both trunnions will resist axial rocking of the gang-beam, owing to their confinement in the eye and front guideway.

In order that the inner ends of the harrow-beams may be kept at a suitable distance 45 from the draft-beam when swung forward parallel with or past it, and may not rise vertically so far as to strike against and abrade it, their upper sides are armed with wear- 50 plates l , and the under sides of the draft-beam opposite these plates are provided with metal runners L , extending transversely there-across, and of such length that they will come above the harrow-beams or part thereof at 55 any reasonable range of adjustment, so as to stop their vertical movement, and in the back-and-forth adjustments run upon the wear-plates and ease the friction. Such, however, form no part of the present invention. The 60 harrow-disks, moving as they often do in damp soil or coming in contact with clods of grass or other matter that will adhere, frequently carry up earthy and fibrous particles, which in the end accumulate so as to 65 seriously clog the machine. It has therefore been customary to apply scrapers to such disks, pressed against them yieldingly and

clearing their concave sides somewhat above and behind the axle. Such scrapers have also been made double-jointed—that is, one 70 arm was spring-pressed toward the disk, while the other arm, pivoted to the lower end of the first and extending above and beneath the mutual pivot, vibrated thereon so as to adjust itself to the face of the disk. Such a 75 scraper I have chosen to illustrate my invention, so far as it regards this feature of the machine. To the rear edge of the gang-beam above such disk I attach a bracket M , having a cylindrical socket m , inclined downward 80 toward the concave face of the adjacent disk, and open at its lower end to receive a coiled spring m' , the top of which sets into a movable cap m^2 , borne upon by a set-screw m^3 , passing through the upper end of the socket. 85 At that end of the bracket nearest to the disk is pivoted an arm N , having a spur n , which comes in line with the open end of the socket and enters into and is pressed upon by the lower end of the spring therein, while to 90 the extreme lower end of the arm is pivoted a scraper-blade O , that may be of hardened metal and have its edge set obliquely to meet the movement of the disk, and thus more efficiently clear it. Were the end of the spring 95 exposed at the rear, as it would be if the walls of the socket ended in an unbroken plane, particles of earth or mud thrown up by the disk might work into it and finally impede its action. Therefore I extend the rear side of 100 the socket down, or, conversely, cut away the other side, as at o , so as to allow the arm and its spur to play up behind the extension, but at no time to project beneath it, thus completely shielding the spring from mud and 105 débris.

I claim—

1. The combination, substantially as hereinbefore set forth, to form a double-jointed hinge, of a plate having trunnions at front and rear, the latter being hooked, an eye into which the rear trunnion hooks, a guideway into which the front trunnion takes, and the removable pin forming one side of such guideway and confining the trunnion set therein. 110

2. The combination, substantially as hereinbefore set forth, of the plate F , having shouldered and hooked rear offset and front offset affording journals, the bracket H' , having an eye at its lower end and a shoulder to match 120 the shoulder on said rear offset, the bracket I' , having the straight guideway opposite the rear eye, and the removable pin i' , whereby the union of the parts is completed.

3. The combination, substantially as hereinbefore set forth, of the bracket M , having downwardly-inclined socket m , with a guard-extension at the rear, the spring inclosed in said socket, and the pivoted scraper-arm N , having spur n , playing in the cut-away portion n' of the socket and shielded by the rear extension thereof and the scraper-blade. 125

4. The combination, substantially as hereinbefore set forth, of the harrow-disk, the

bracket M, secured to the rear edge of the gang-beam adjacent to said disk, the cylindrical socket m upon said bracket directed obliquely downward toward the adjacent disk 5 and extended at the rear to form a shield, the spring sitting within said socket and the cap receiving the head of the spring, the set-screw pressing upon said cap, the scraper-arm N, pivoted to the bracket adjacent to the disk

and depending theretoward and having a spur n , which enters the front cut-away portion n' of the socket and receives the lower end of the spring, and the scraper-blades pivoted to the lower end of the arm.

P. E. LITTLE.
